UNITED STATES PATENT OFFICE

2,573,000

RELAY

Albert W. Fischer, Highland Park, Mich., assignor to General Motors Corporation, Detroit, Mich., a corporation of Delaware

Original application August 16, 1943, Serial No. 498,777. Divided and this application August 19, 1944, Serial No. 550,227

2 Claims. (Cl. 200—104)

1

This invention relates to relay means and more specifically to sensitive relay control means actuated by very small electrical currents.

There are many instances in which minute current flow is called upon to actuate control apparatus and this is usually accomplished through relay means of some sort. A majority of them are designed to be operated by substantial currents and would not be affected by very small ones. One example of an installation in which a very sensitive relay or galvanometer relay is used is in a temperature recording mechanism such as shown in my copending application Serial Number 498,777, filed August 16, 1943, subsequently abandoned, of which this is a division.

It is therefore an object of my invention to provide a very sensitive relay means.

It is a further object of my invention to provide a relay actuated by very small currents.

With these and other objects in view which will become apparent as the specification proceeds, the embodiments of my invention will be best understood by reference to the following specification and claims and the illustrations in the accompanying drawings, in which:

Figure 1 is a vertical section through the galvanometer relay.

Figure 2 is a front elevation of the relay taken on line 2—2 of Figure 1.

Figure 3 is a sectional view taken on line 3—3 of Figure 1.

Figure 4 is a rear elevation of the relay taken on line 4—4 of Figure 1.

The galvanometer relay indicated generally at 14, consists of a substantially rectangular plate 192 having on its rear face a plurality of spaced magnetic core means indicated generally at 194 and 196 on opposite sides of the center. These core means are each formed of a cylindrical permanent magnetic member 195 and 197 which may be of "Alnico" or some similar material, and a central soft iron pole piece 199 and 201 respectively. In each of these core means there is provided a small circular air gap 198 and 200 in which a continuous radial magnetic field is present and in which are located two coils 202 and 204. These coils are connected in series in the bridge circuit and are supported by thin circular hoops 206—208 which form the opposite ends of a transverse balanced bar 210 which acts as the actuating member for the galvanometer. The two coils 202 and 204, while being connected in series, are so wound that when current flows through them in one direction their magnetic fields will interact with the fields in the gaps so

2

that one of the hoops will be attracted or pulled down into the air gap, while the other will be repulsed, thus giving a definite torque for operating purposes.

5 The central portion of the transverse member 210 is secured to a member 212 which has a transverse opening 214 therethrough in which are secured small threaded screws 216 to each of which are permanently connected one end of two thin metal strips 218 and 220. The opposite end of the thin strip 218 is adjustably secured to an upright member 222 mounted on the insulating base 192, but terminating in a similar threaded screw member 224 which extends through an 10 opening in the upright member 222, and has a pair of nuts on opposite sides of the member which can be threaded to different adjusted positions to stress the thin ribbon. In like manner, the thin strip 220 terminates in a threaded member 226 which is secured to a rotatable sleeve 228 mounted in an upright bracket 230 also carried by the member 192. This sleeve 228 has a small toothed gear 232 rigidly secured thereto by which the sleeve may be turned. Thus turning this one 15 end of the flat strip 220 will cause a torque in one direction or the other about this flexible axis and cause the galvanometer movement to be biased in the turned direction. Mating with this gear 232 is a small gear 258 which is mounted on a shaft extending through the member 192 which can be turned by actuation of the zero adjustment of knob 20. Of course, the tension on these two thin strips 220 and 218 should be sufficient to support the galvanometer movement.

20 An opening 234 through the central portion of the insulating support 192 accommodates the movable contactors carried by the galvanometer movement. These contactors consist of two spaced contact points 236 and 238 which may be 25 of platinum carried by the member 212 of the galvanometer movement and insulated from each other, the member 212 being of insulating material. These two spaced contacts therefore assume a position between two adjustable contactors 242 and 244 carried by two bendable spring strips 246 and 248 having one end thereof rigidly secured to the member 192 and having their 30 opposite ends interconnected by an insulating cross member 250 which in turn carries an armature member 252, in juxtaposition to a small electromagnet 254 mounted in an opening 256 likewise provided in the insulating member 192. Thus these spaced contacts 242 and 244 may be 35 vibrated back and forth when alternating current is supplied to the small solenoid 254 and

move over the surface of the ends of the members 236 and 238 and maintain the same clean. In operation the gear 232 is turned by suitable means (not shown) until the arm 212 is positioned midway between contactors 242 and 244. The coils 204 and 206 are as previously mentioned, connected in series and are connected to the circuit to be measured, such for example as a balanced bridge. The coil 256 is connected to a separate source of power so that it may continuously provide vibrations to the contacts 242 and 244 which are adapted to control operating, indicating or recording means so that there will be a good conducting engagement maintained between 242 and 244 and their associated contacts 236 and 238 respectively. Any current flowing in the circuit through the coils will therefore create forces tending to rotate the arm 210 around the axis of the strips 218 and 220 and cause closure of the associated contacts 242-236 or 244-238 depending upon the direction of flow and the amount of said current. Therefore it will be seen that I have provided a galvanometer movement in which torque is provided by two spaced coils, causing actuation in opposite directions about a flexible axis which provides a very sensitive movement, and means for keeping the contact clean and reducing surface resistance between the spaced adjustable points and the ends of the two movable contact means carried by the galvanometer movement. This construction also provides a zero adjustment by tensioning the flexible strip in one direction or the other about its axis by a manually adjustable means.

I claim:

1. In relay means, permanently magnetized means, pivotally movable means mounted in juxtaposition to the first named means having an adjustable bias about its axis, coil means mounted on said pivotal means on opposite sides of the pivot so wound and connected that the passage of current there through will cause a torque about the pivot in the same direction, a plurality of contact means carried by the pivotal means, spaced adjustable contact means mounted for

limited movement in the plane of the pivotal means engageable by the contact means carried by the pivotal means to provide switching means, and magnetic vibratory means for simultaneously vibrating the spaced adjustable contact means in its plane of movement relative to the pivoted contacts to maintain good contact surfaces.

2. In relay means, a base, movable contact means pivotally mounted on said base, bendable means having one end anchored to said base in juxtaposition to the pivotal means and deformable in a radial plane with respect to the pivotal means, a plurality of contact means adjustably mounted in spaced relation on said bendable means for engagement with the pivotally movable contact means at different positions of its rotative movement, magnetic vibratory means mounted on said base adjacent the free end of the bendable means to cause the latter to vibrate when the magnetic means is energized and thus to cause relative movement between the adjustable contact means mounted on said bendable means and the contact means on the pivotally mounted means to cause a cleaning movement.

ALBERT W. FISCHER.
